UNITED STATES PATENT OFFICE.

LEWIS T. RHOADES, OF MONT CLARE, PENNSYLVANIA, ASSIGNOR TO NEW YORK COIL COMPANY, INCORPORATED, OF NEW YORK, N. Y.

LOCKING DEVICE.

1,248,011.

Specification of Letters Patent.

Patented Nov. 27, 1917.

Application filed May 23, 1917. Serial No. 171,352.

To all whom it may concern:

Be it known that I, LEWIS T. RHOADES, a citizen of the United States, residing at Mont Clare, in the county of Montgomery and State of Pennsylvania, have invented certain new and useful Improvements in Locking Devices, of which the following is a specification.

My invention consists of an improved locking device which is particularly adapted for preventing the theft of automobiles.

One object of my invention is to provide a locking device which will prevent an unauthorized person from operatively connecting the engine with the driving gear, but which will not lock the road wheels or steering means. Thus, while my invention locks the automobile against movement by the engine, it will permit the automobile to be moved a short distance by hand if such a contingency arises, such for example as a fire in the garage, or the building in front of which the automobile is standing.

Another object is to so make my invention that it can be easily and quickly moved and applied in its operative position and when not desired for locking purposes, can be moved and securely held in an inoperative position and in readiness to be again moved into an operative position and applied without the employment of a key, the key only being necessary to unlock the device from its locking position.

A further object is to so make my invention that it will be free of any exposed parts which could be cut, loosened, or removed by a thief.

A still further object is to so construct my invention that it will be particularly adapted for locking connection with transmission levers of various shapes and sizes.

These objects, and other advantageous ends which will be described hereinafter, I attain in the following manner, reference being had to the accompanying drawings in which

Figure 1 is a top plan view of my improved locking device showing it secured to the supporting structure, such as the heel board of an automobile seat, a fragment of the heel board being shown in section.

Fig. 2 is a side view of Fig. 1.

Fig. 3 is an enlarged sectional view of the lock casing taken on the line 3—3 of Fig. 4.

Fig. 4 is a section through the lock casing taken on the line 4—4 of Fig. 3.

Fig. 5 is an enlarged section taken on the line 5—5 of Fig. 1.

Fig. 6 is a section taken on the line 6—6 of Fig. 5.

Fig. 7 is an enlarged fragmentary section on the line 7—7 of Fig. 1.

Fig. 8 is a side elevation of the retaining means for the lock casing.

Fig. 9 is a front view of Fig. 8.

Fig. 10 is a perspective view illustrating how my improved locking device prevents the operation of the transmission lever.

Fig. 11 is a perspective view illustrating my improved locking device in an inoperative position.

Referring to the drawings, 1 represents the base or heel board of an automobile seat and to the outer surface of this heel board I secure a metallic disk 2 by two button headed bolts 3 and 4. These bolts have portions 5 which are square or angular in cross section and fit within angular recesses in the heel board 1.

The outer ends of the bolts 3 and 4 extend through the disk 2 and are provided with square nuts 7 which bind the disk to the outer surface of the board 1. A lug 8 is either made integral with the disk 2 or securely held within a countersunk opening in said disk as clearly illustrated in Fig. 5. This lug 8, at its outer end, is screw-threaded and designed to screw within a tapped hole 9 in a recessed cap 10. The cap 10 has a recess 11 which, when the cap is screwed on the lug 8, forms a housing or enclosure for the lug 8 and the nuts 7, thus preventing the manipulation of said nuts.

The inner diameter of the recess 11 is such that the nuts 7 are prevented from turning when the cap 10 has been screwed on the lug 8 as shown in Fig. 5. Fig. 6 clearly shows the position of the nuts 7 with respect to the inner diameter of the recess 11 so that the bolts will not become loosened due to any vibration of the automobile.

A staple 12 extends through the cap 10 and has its ends riveted on the inner surface providing said recess. The staple 12 and cap 10 are preferably so formed with respect to the disk 2 that when the cap is tightly screwed on the lug 8, the legs of the staple will be included in a plane substantially at

right angles to the plane of the floor as clearly illustrated in Figs. 2, 10, and 11.

A bar 13 has an eye 14 through which the staple 12 freely passes so that said bar is free to pivot and freely move around said staple. The bar 13, at its free end, extends through a casing 15. This casing is preferably made of ductile metal and has a cover 16 which fits within a recess 17 and 10 rests on a ledge 18 forming the bottom of said recess.

The upper edge of the cover 16 is beveled or chamfered as shown at 19 and after the cover has been inserted within said recess, 15 the edge portion 20 of the casing 15 is bent or compressed over the beveled edge of the cover as clearly shown in Figs. 4 and 7, thus securely locking the cover to the casing.

The bar 13 has a series of holes 21 extending transversely therethrough and any one of these holes is capable of being engaged by a screw 22 having its head projecting entirely within the casing 15 and its opposite end fitting a threaded hole 23 in 25 the casing 15.

The screw 22 is preferably made of such length that it will not entirely pass through to the outer surface of the casing 15 and the outer portion of the screw hole in the casing can be covered with sealing material 24, so that the butt end of the screw will not be exposed.

By the provision of the holes 21 in the bar 13, the casing 15 can be secured to the 35 bar 13 at various distances from the heel board 1 for a purpose hereinafter described. The casing 15 is entirely closed with the exception of an opening 25 provided between the end 26 of a rib 27, and the side portion 40 28 of the casing. This opening is designed to permit the free end 29 of a hasp 30 to move therein. The hasp 30 has its end 31 pivoted between two ears 32 and 33 respectively formed on the bottom of the casing 45 15 and the cover 16.

The hasp 30 is of a width substantially equal to the distance between the inner surfaces of the cover 16 and the bottom of the casing 15, so that when the end 29 of the 50 hasp is within the opening 25, it completely closes said opening against the insertion of a tool or other instrument.

The opening 25 is in alignment with the screw 22 so that when the hasp is open, a 55 screw-driver can be inserted through the opening 25 to remove the screw 22 if it is desired to change the position of the casing on the bar 13. However, when the hasp is in its locked position, the opening 25 will 60 be closed against the insertion of any instrument as previously stated and the screw 22 cannot be actuated.

The cover 16 and the bottom of the casing 15 are provided with V-shaped recesses 34 65 and 35 respectively and the rib 27 also has

an inwardly dipped portion 36 which registers with the recesses 34 and 35.

The hasp 30 has an outwardly curved portion 37 which bridges the recesses 34, 35, and dipped portion 36 of the rib 27 as 70 clearly shown in Fig. 3.

The end 29 of the hasp 30 is also curved, the curvature being substantially in the arc of a circle having its center coincident with the pivotal axis of the hasp. The extreme 75 inner end 38 of the hasp 30 is provided with a plurality of notches 39 arranged at increasing distances inwardly from the free end. Any of these notches is capable of being engaged by a bolt 40 which is slidably mounted in two lugs 41 which are spaced apart and extend inwardly from the cover 16. The end 42 of the bolt is beveled and a coiled spring 43 is interposed between one of the lugs 41 and a shoulder 44 80 on said bolt so as to move the bolt in a forward direction and to hold the bolt into engagement with a respective notch 39.

A lock 45 is secured within the cover 16, and this lock can be of any desirable construction of the rotatable barrel type. The casing 46 of the lock is preferably provided with a lug 47 designed to fit within a groove 48 in the cover 16 to prevent rotation of the casing when the barrel of the lock is rotated by the insertion of the proper key. 90

A tongue 49 is rotatable in conjunction with the barrel of the lock and is designed to engage a finger 50 which is secured to the bolt 40 so that a rotation of said tongue 49 100 will slide the bolt 40 longitudinally against the action of the spring 43 to release the end 29 of the hasp 30.

A torsion spring 51 is mounted between the ears 32 and 33 and serves to move the 105 hasp 30 into an open position when released by the bolt 40. The hasp 30 is designed to secure the transmission lever 52 to the casing 15, the bar 13 being swung into position so as to locate the transmission lever within 110 the V-shaped recesses 34 and 35. The hasp 30 can then be swung on its pivot to embrace the transmission lever and the bolt 40 will move into the notch which is in its path of movement. 115

By this arrangement of the V-shaped recesses and the outwardly curved portion 37 of the hasp 30, the device accommodates itself to transmission levers of various sizes and cross sections, the lever being snugly 120 held between the V-shaped recesses and the portion 37 of the hasp 30.

To guard against movement of the casing 15 lengthwise of the transmission lever 52, I provide outwardly extending flanges 53 125 and 54. These flanges provide an extended bearing in line with the V-shaped recesses 34 and 35 and serve to bind against the transmission lever to prevent sliding movement of the casing 15 lengthwise of said lever. 130

ver, thus preventing the movement of the transmission lever to a degree sufficient to throw the gears into operative connection with the engine.

5 To remove the casing 15 from the transmission lever, it is merely necessary to insert the proper key within the lock and turn the same until the tongue 49 moves the bolt 40 out of engagement with the hasp 30.

10 The torsion spring 51 will then move the hasp into an open position to free the transmission lever.

In order to secure the device in an inoperative position and out of the way of the 15 driver, I provide a retaining member 55 which is of V-shape cross section, substantially corresponding to the contour of the recesses 34 and 35 in the casing 15 above mentioned.

20 The retaining member 55 has an end portion 56 provided with a bolt hole 57 whereby it can be secured to the heel board 1 at a distance from the disk 2 and cap 10 to permit the casing 15 and bar 13 to be swung 25 into a position under the seat and so that the retaining member 55 will project between the casing 15 and the hasp 30.

The lower portion of the retaining member is provided with a leaf spring 58 which 30 is secured by a rivet or other suitable means 59, the opposite end 60 of said spring being free to slide under the forward end 61 of the retaining member 55. The portion of the spring intermediate of its ends is bowed 35 downwardly as clearly shown in Fig. 8 and is designed to be engaged by the inner surface of the portion 37 of the hasp 30, thus preventing the notched end 29 of the hasp from moving sufficiently far within the casing 40 into to be engaged by the bolt 40.

The retaining member 55 is positioned close to the floor so that when the casing is mounted thereon, the spring 58 will serve both to prevent the hasp from moving into 45 a locked position, and also to prevent noise due to vibration.

The torsion spring 51 will also act to move the outer surface of the portion 37 of the hasp 30 into engagement with the floor.

50 Thus, the device will be firmly held in an inoperative position and when required for use, it is merely necessary to pull the casing 15 off of the retaining member 55 to release the hasp 30 and the bar 13 can then be 55 swung on the staple 12 to bring the casing 15 into engagement with the transmission lever where it will be locked by pressing the hasp 30 to move the end 29 within the casing to be engaged by the bolt 40.

60 Since the transmission lever cannot be moved to effect the movement of the transmission gears, it is impossible when the device is in its locked position to connect the engine's power with the drive wheels. By 65 preventing the hasp from engaging the bolt

when the device is in an inoperative position on the retaining member 55, it is unnecessary for the operator to use a key to first unlock the device when it is applied to the transmission lever, thus the retaining 70 member performs a double purpose. It retains the casing and bar in an inoperative position, and prevents the locking of the hasp.

By providing the holes 21 in the bar 13, 75 the casing 15 can be secured to said bar at various distances from the heel board 1 in order to fit against transmission levers which are at various distances from the heel board, since in various makes of automobiles the 80 distance from the transmission lever to the heel board varies. It will be further noted that when the casing 15 is locked on the transmission lever, it is impossible to rotate the cap 10 for the reason that the bar 13 is 85 secured against rotation relatively to the casing 15 by the screw 22. Thus, the device cannot be detached from the disk 2 when in a locked position.

It will be evident that my invention is 90 applicable due to its novel construction to all makes of cars without resorting to the weakening of the lever such as would be caused by boring holes therein, and such would be necessary if the lock was fitted directly thereto.

Furthermore, since the lock is not connected to the transmission lever when the car is being driven, the possibility of interfering with the ready operation of the lever 100 is obviated.

While I have described my invention as taking a particular form, it will be understood that the various parts of my invention may be changed without departing 105 from the spirit thereof, and hence I do not limit myself to the precise construction set forth, but consider that I am at liberty to make such changes and alterations as fairly come within the scope of the appended 110 claims.

Having thus described my invention, what I claim as new and desire to secure by Letters Patent is:

1. The combination with an automobile, 115 of an operating lever, a supporting structure, independent locking means including a lock casing, a hasp adapted to secure the lever to the casing, a retaining member secured to the supporting structure, said casing being designed to be swung over said retaining member to permit the latter to extend between the casing and the hasp, substantially as described.

2. The combination with an automobile, 125 of an operating lever, a supporting structure, independent locking means including a lock casing having a portion designed to engage the lever, a hasp adapted to secure the lever to said portion of the casing, a retain-

- ing member secured to the supporting structure, said casing being designed to be swung into a position to permit the retaining member to extend between said portion and the 5 hasp, locking means in said casing for engagement with the hasp, and means on said retaining member designed to hold said hasp out of engagement with the locking means, substantially as described.
- 10 3. The combination with an automobile, of an operating lever, independent locking means including a lock casing, a hasp adapted to secure the lever to the casing, a retaining member secured to said supporting 15 structure above but near the floor of the automobile, said casing being designed to be swung into a position to permit the retaining member to extend between the casing and the hasp, locking means in said casing for 20 engagement with the hasp, and a spring designed to hold said hasp out of locking engagement with the locking means of the casing and in engagement with the floor, substantially as described.
- 25 4. The combination with an automobile, of an operating lever, a supporting structure, bolts extending through the supporting structure and having portions preventing their rotation in said supporting structure, a 30 member secured to the supporting structure by the nuts of the bolts, said member having a lug projecting therefrom, a cap designed to be secured to said lug, said cap having a recess into which the nuts of the bolts extend, attaching means on said cap, a bar movably connected to the attaching means, and locking means carried by said bar and designed to be locked to said lever, substantially as described.
- 35 40 5. The combination with an automobile, of an operating lever, a supporting structure, a bar movably connected to said supporting structure, and having a series of holes therein, a locking casing adapted to be 45 secured to said lever, and means in said casing capable of passing into any of said holes to secure the casing to the bar at various distances from the supporting structure, substantially as described.
- 50 55 6. The combination with an automobile, of an operating lever, a supporting structure, independent locking means including a lock casing having a substantially V-shape recessed portion designed to embrace the lever, a hasp adapted to secure the lever within said recess, a retaining member secured to the supporting structure, said casing being designed to be swung over said retaining member to permit the latter to extend between the recessed portion and the hasp, substantially as described.
- 60 65 7. The combination with an automobile, of an operating lever, a supporting structure, independent locking means including a lock casing having a substantially V-shape
- recessed portion designed to embrace the lever, a hasp adapted to secure the lever within said recess, a retaining member secured to the supporting structure, said casing being designed to be swung over said retaining member to permit the latter to extend between the recessed portion and the hasp, substantially as described. 70
- 75 8. The combination with an automobile, of an operating lever, independent locking means including a lock casing having a substantially V-shape recessed portion designed to embrace the lever, a hasp adapted to secure the lever within said recess, a retaining member secured to said supporting structure above but near the floor of the automobile, 80 said casing being designed to be swung over the retaining member to permit the latter to extend between said recessed portion and the hasp, locking means in said casing for engagement with the hasp, and a spring 85 designed to hold said hasp out of locking engagement with the locking means and in engagement with the floor, substantially as described.
9. The combination with an automobile, 90 of an operating lever, a supporting structure, independent locking means including a lock casing having a substantially V-shape recessed portion designed to embrace the lever, a hasp adapted to secure the lever within said recess, a retaining member secured to the supporting structure, said casing being designed to be swung over said retaining member to permit the latter to extend between the recessed portion and the hasp, said 95 retaining member being substantially V-shape in cross section and corresponding to the shape of the recess in the casing, substantially as described.
10. The combination with an automobile, 100 of an operating lever, a supporting structure, bolts extending through the supporting structure and having portions preventing their rotation in said supporting structure, a member secured to the supporting 110 structure by the nuts of the bolts, said member having a threaded lug projecting therefrom, a cap designed to be screwed on said lug, said cap having a recess into which the nuts of the bolts extend, attaching means 115 on said cap, a bar movably connected to the attaching means, and locking means carried by said bar and designed to be locked to said lever, substantially as described.
- 120 11. The combination with an automobile, 125 of an operating lever, a supporting structure, bolts extending through the supporting structure and having portions preventing their rotation in said supporting structure, a member secured to the supporting 130

structure by the nuts of the bolts, said member having a threaded lug projecting therefrom, a cap designed to be screwed on said lug, said cap having a recess into which the nuts of the bolts extend, a staple having its ends secured within said cap, a bar having an eye through which the staple extends, and locking means carried by said bar and designed to be secured to said lever, substantially as described.

12. The combination with an automobile, of an operating lever, a supporting structure, bolts extending through the supporting structure and having portions preventing their rotation in said supporting structure, a member secured to the supporting structure by the nuts of the bolts, said member having a threaded lug projecting therefrom, a cap designed to be screwed on said lug, said cap having a recess into which the nuts of the bolts extend, said nuts having angularly disposed surfaces, the inner surface of said recessed cap being designed to be moved in close proximity to said surfaces of the nuts to prevent their accidental rotation when the cap is in place, attaching means on said cap, a bar movably connected to the attaching means, and locking means carried by said bar and designed to be locked to said lever, substantially as described.

13. A locking device of the character de-

scribed including a casing having a recess therein, a hasp movably secured to the casing and to bridge said recessed portion, said casing having an opening therein through which one end of the hasp can be moved, a bar extending into said casing, said casing having a threaded hole in alignment with said opening, said bar having a hole through which a screw can be inserted and screwed into said threaded hole in the casing, substantially as described.

14. A locking device of the character described including a casing having a recess therein, a hasp movably secured to the casing and to bridge said recessed portion, said casing having an opening therein through which one end of the hasp can be moved, a bar extending into said casing, said casing having a threaded hole in alignment with said opening, said bar having a series of holes extending transversely thereof, and a screw designed to be inserted through any of said holes and screwed into the threaded hole in the casing, substantially as described.

In testimony whereof I have signed my name to this specification in the presence of two subscribing witnesses.
